[57] CLAIM

The ornamental design for a basketball backboard cover, as shown and described.

DESCRIPTION

FIG. 1 is a perspective view of a basketball backboard cover showing the new design, the basketball hoop shown in broken lines is for illustrative purposes only and forms no part of the claimed design.

FIG. 2 is a top plan view thereof;

FIG. 3 is a bottom plan view thereof;

FIG. 4 is a front elevational view thereof;

FIG. 5 is a rear elevational view thereof;

FIG. 6 is a side elevational view thereof the opposite side elevational view being identical.

FIG. 7 is an enlarged fragmented perspective view of one aspect of the cover shown in FIG. 5.

FIG. 8 is a rear elevational view thereof; and,

FIG. 9 is a side elevational view thereof, the opposite side elevational view being a mirror image.
